DESIGN FOR A BODY FOR A STRINGED MUSICAL INSTRUMENT

Frank R. Johnson, St. Charles, Ill.

Application October 21, 1935, Serial No. 59,146

Term of patent 3½ years

To all whom it may concern:

Be it known that I, Frank R. Johnson, a citizen of the United States, residing at St. Charles, Kane County, Illinois, have invented a new, original, and ornamental Design for a Body for a Stringed Musical Instrument, of which the following is a specification, reference being had to the accompanying drawing, forming a part thereof.

Fig. 1 is a front elevational view of the body

for a stringed musical instrument showing my design; and

Fig. 2 is a side elevational view thereof.

The dominant feature of the design is shown in full lines.

I claim:

The ornamental design for a body for a stringed musical instrument, as shown and described.

FRANK R. JOHNSON.
